SHOULDER STRAP HOLDER

Pearl E. Switzer, Cleveland, Ohio

Application May 10, 1933, Serial No. 670,366

3 Claims. (Cl. 24—73)

This invention relates to a holding device for preventing the displacement or "slipping" of lingerie straps or ribbons from the shoulder of the wearer.

5 This tendency of a shoulder strap to slip is a source of much annoyance and sometimes embarrassment to women. In an effort to prevent this slipping, the strap has often been pinned directly to an outer garment, or, by the use of devices permanently attached to the apparel. In the first instance, the strap does not lie natural on the shoulder and gives rise to an uncomfortable feeling augmented by the contact of the pin with the bare flesh. In the second instance the 10 devices must be removed each and every time the garment is sent to the cleaners, else the devices are liable to be torn off with consequent damage to the dress material. Other forms of devices employed are open to criticism on the grounds that they are not easy to manipulate 15 or are prone to release when in use.

It is my aim to provide a removable strap fastener that may be easily manipulated by women, both to attach the same to a garment, and to 20 catch up and hold the strap. By virtue of my novel device, the wearer may rest assured that the strap will be properly held without discom- 25 fort to the wearer and further will not be released inadvertently through any separation 30 of the device. However, release of the strap may be had easily and instantaneously with a manual manipulation that is no more difficult to perform, and as speedy as a buttoning operation. It is 35 of considerable advantage to be able to quickly release or catch up the ribbon strap, with literally a flip of the hand, since time is not lost in undoing and doing pins or pulling open hooks and eyes or performing other operations that necessitate the use of both hands to properly af- 40 fix or release the devices.

Other objects and advantageous features of this invention are to be noted in the following detailed description and accompanying drawing, wherein like characters of reference designate 45 similar parts, and wherein:—

Figure 1 illustrates the application of my novel shoulder strap holder in securing ribbons, straps, or the like in place on the wearer's shoulder.

Figure 2 is a detail of the strap holder illustrating the manner in which it may be attached to a foundation garment.

Figure 3 is a plan of the strap holder illustrating the manner in which the parts may be manipulated manually to close the same.

Figure 4 is a plan of the novel strap holder

illustrating the same in closed position as it would normally appear when in position for its intended purpose.

Figure 5 is an elevation of the holding part of the device which engages with a shoulder strap 60 to prevent displacement thereof.

Figure 6 is a section taken on the line 6—6 of Figure 5.

Figure 7 is a section illustrating the form of an alternative type of holding part which may 65 be used in place of that shown in Figure 5.

Figure 8 discloses the manner in which the holding part of Figure 5 may be permanently attached to the attaching member.

Figure 9 discloses an alternative form of hold- 70 ing part.

Generally speaking, this novel strap holder consists in a pin having a pinning leg, by means of which the same may be removably attached to a garment, plus a holding element for looping 75 around a lingerie strap, the holding element being permanently attached at one end to the pin and being removably attached to the pin at its opposed end.

With reference to the drawing, the novel strap 80 holder is best shown in Figure 3 and Figure 4, wherein one element of the device is shown as comprising a pin A having a pinning leg 1 and a bar portion 2 made up of a continuous length of metal that is turned to provide a closed loop 3. 85 The keeper is provided for the pinning leg in the form of a head portion 4 having an integral de- pending lug 5 that extends below the bar portion 2 for the purpose to be hereinafter described. This pin may take the form of an ordinary safety 90 pin, however, is possessed of the additional fea- ture of the lug 5 which has a peculiar cooperation with the other element of the device to accom- plish a particular and useful end.

Referring now to Figures 5 and 8, the element 95 which is intended to be slipped around or looped under the shoulder strap, is illustrated by the numeral 7 as comprising a flexible length of ma- terial having the end portions provided with closed loops 8 and 9. This holding element is 100 preferably made up of a core of round rubber elastic as shown at 10, in Figure 6, covered with a woven braiding 12, or, on the other hand, may be made up simply of a woven fabric or other ma- terial which will serve for the purpose intended. 105 Furthermore, the core 10 may be of rectangular configuration as shown at 11 in Figure 7 covered with a woven braiding 12.

I preferably attach the holding element 7 to the pin A in the zone of the closed loop 3 of the 110

pin either by inserting the free end of the holding element 7 through the loop and thereafter forming a closed loop in the holding element by sewing, or forming the closed loop in the holding element first and then manipulating it along the pinning leg and around the loop in a manner which is well known.

With the parts in assembled relation, the wearer may, conveniently attach the same to an outer garment after which the holding element may be looped under the shoulder strap or ribbon and affixed to the head portion of the pin A, as will now be described.

Referring to Figure 2, as shown, the pin A is pinned to the shoulder of an outer garment, preferably along a seam. While this operation of attaching the pin takes place, the looped end 9 of the holding element preferably hangs free.

After the pin is attached, this end is taken in the fingers and threaded under the strap which in turn is sustained thereby, as shown in Figure 4. Then, as illustrated in Figure 3, the closed loop 9 is moved axially along the pin head 4 and passed over the lug 5 so that the parts in final closed position will be substantially the same as that shown in Figure 4. The lug member 5 prevents the free end of the holding element from slipping rearwardly off the head of the pin and thus prevents dissociation of parts and subsequent release of the shoulder strap to the annoyance of the wearer. Release may be had by simply manipulating the end of the loop rearwardly over the lug and off the head of the pin. This is easy to perform and quickly accomplished.

It will be observed that the loop 9 is preferably circular in end view, as shown in Figure 5. By virtue of this arrangement, the loop may be elongated or distended to allow it to pass over the lug 5, however, I prefer that the inside diameter of the loop be such that when the same comes to rest against the lug 5, the loop will closely embrace the bars 1 and 2 of the pin and will tend to be prevented from axial movement away from the pin through such association. Where the holding element is made with an elastic core, the inherent resiliency of the material will tend to draw the loop tightly around the pinning leg and bar, thus preventing movement along the pin.

In Figure 9 I have shown an alternative form of holding part that may be employed advantageously in place of the part 7 shown in Figure 5. This member preferably consists of a resilient member 13 which takes the form of a rubber band which is enclosed in a tube of material 14, such as that commonly used in covering buss wire, and is known in the trade as "spaghetti". The ends of the rubber band extend from the tube as loops and accordingly one loop may be attached to the pin in the zone of its closed loop, in a manner which may be readily apparent, and the other end is then free to be removably attached to the head end of the pin in a manner consistent with that set forth with regard to the part 7.

It will be apparent that after the holding part is mounted on the pin and looped under the strap, the "spaghetti" covering may be shifted along the rubber band toward the head portion

4 to reduce the effective length of the loop and thus prevent dissociation of the parts through abutment against the lug 5.

In conclusion, it may be said that I have provided a very simple device that is economical to manufacture and which should have a wide demand, particularly in view of its utility and the ease with which it may be manipulated. It will be readily seen that the parts are not prone to become dissociated under any and all conditions of use.

Although I have shown and described this novel article of manufacture as being preferably employed for the purpose of retaining shoulder straps in position, it is well within the scope of this invention to employ it in other and further capacities without departing from the spirit of this invention.

Having thus described my invention, what I claim as new and desire to secure by Letters Patent of the United States, is—

1. As an article of manufacture, a holding device for shoulder straps or the like on women's garments, comprising, in combination, a pin having a pinning leg, a bar portion, a loop, and a head, and a flexible holding element mounted to cooperate with the strap to maintain the same in position on a wearer's shoulder, means for attaching said holding element to said pin in the zone of the closed loop, means for attaching said holding element to said pin in the zone of the head portion including a loop movable axially of the pin and over the head portion to encompass and embrace the pinning leg and bar portion of the pin.

2. As an article of manufacture, a holding device for shoulder straps or ribbons on women's garments, which comprises, in combination, a pin adapted to be attached to an outer garment along the shoulder seam thereof, said pin comprising a bar portion and a pinning leg joined by a closed loop, a head portion and a pliable holding element to be trained around a strap or ribbon, said holding element comprising a resilient core, a woven fabric encompassing said core, and a closed loop at the fixed end of the holding element for permanently attaching said holding element to said pin, a second closed loop formed at the free end of said holding element for engaging said pinning means in the zone of the head portion and for encompassing said bar portion and said pinning leg, and means for preventing axial movement of said free end in at least one direction, comprising a lug formed on said head and depending beyond said bar portion and normally lying in the path over which the free end travels.

3. As an article of manufacture, a holding device for shoulder straps, which comprises, in combination, a flexible holding element having a closed loop at each end, pinning means carried by one of said loops, a head on said pinning means, the other of said loops being movable axially along said pin and over said head to attach the same thereto, and means for securing said loop to said head comprising a lug formed as a part of said head, and a resilient core for said holding element for embracing and gripping said pin.
